(57) **CLAIM**

We claim the ornamental design for a faucet with handles, as shown and described.

DESCRIPTION

FIG. 1 is a front, top, left side perspective view of a faucet with handles showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and

FIG. 8 is a front, bottom, left side perspective view thereof;

FIG. 9 is a front, top, left side perspective view of the handle shown in FIG. 1;

FIG. 10 is a front view thereof;

FIG. 11 is a rear view thereof;

FIG. 12 is a left side view thereof;

FIG. 13 is a right side view thereof;

FIG. 14 is a top view thereof;

FIG. 15 is a bottom view thereof; and

FIG. 16 is a front, bottom, left side perspective view thereof;

FIG. 17 is a front, top, left side perspective view of the faucet shown in FIG. 1;

FIG. 18 is a front view thereof;

FIG. 19 is a rear view thereof;

FIG. 20 is a left side view thereof;

FIG. 21 is a right side view thereof;

FIG. 22 is a top view thereof;

FIG. 23 is a bottom view thereof; and,

FIG. 24 is a front, bottom, left side perspective view thereof.

Broken lines of the disclosure represent portions of the faucet with handles that form no part of the claimed design.

1 Claim, 15 Drawing Sheets
